COIN CHUTE

Walter A. Tratsch, Chicago, Ill.

Application December 1, 1933, Serial No. 700,421

2 Claims. (Cl. 194—101)

This invention relates to coin chutes.

It is an object of this invention to provide an improved coin chute which is relatively simple and inexpensive in construction and efficient in use.

Another object of this invention is to provide an improved multiple or gang coin chute device for multiple compartment vending machines and other coin operated machines.

10 A further object of the present invention is to provide a multiple or gang coin chute device which includes a plurality of coin chutes, one for each vending unit or compartment in the vending machine with which the device may be associated; which is compact in size; and which has an operating mechanism associated with the gang of coin chutes in such a manner that certain parts of the operating mechanism are common to all the coin chutes so that space is conserved, the 15 necessity for a separate operating mechanism for each chute is eliminated, the number of operating parts needed in association with the gang coin chute device is reduced to a minimum, and the duplication of operating parts eliminated.

20 25 An additional object of the invention is to provide a multiple or gang coin chute device having a plurality of coin chutes arranged in a row and in a substantially fan-shaped or truncated V-shaped formation, and converging at their lower 20 ends toward a common apex so that the transverse or overall width across the lower end of the gang of chutes is considerably less than the overall distance across the top of the gang chutes. This accommodates the overall horizontal width 30 of the gang of chutes at their lower ends to the mouth of the coin distributor with which the gang of chutes is associated and the horizontal width of which is considerably less than that of the vending machine cabinet with which the 35 40 gang of chutes and the coin distributor are associated.

The drawing illustrates a preferred form of the invention and therein:

Fig. 1 is a front elevational view of a preferred form of the new gang coin chute device;

Fig. 2 is an end elevational view of the same, taken on line 2—2 in Fig. 1;

Fig. 3 is a vertical sectional view on line 3—3 in Fig. 1;

50 Fig. 4 is a fragmentary horizontal sectional view on line 4—4 in Fig. 3; and

Fig. 5 is a fragmentary sectional view on line 5—5 in Fig. 4.

A preferred form of the invention is illustrated 55 in the drawing, is therein generally indicated at

10, and is shown, for the purpose of illustration, as associated with a conventional coin operated device in the form of a vending machine 11 of the type which embodies a plurality of vending units or compartments (not shown).

5 The new coin chute device 10 includes a plurality or gang of coin chutes 12, it being understood that there is one coin chute 12 for each vending unit or compartment in the vending machine 11 with which the device is associated. 10 This number depends, of course, upon the size and type of vending machine, or other coin operated machine with which the device is to be associated. These chutes 12 are formed between a plate 14 and a plate 19 which form, respectively, the front 15 and rear walls of the chutes 12.

15 The coin chutes 12 are arranged in a row and this row is divided into groups which are arranged on opposite sides of the vertical center or midline 13 of the device. All of the chutes 20 12 converge at their lower ends toward a common apex or point as shown in Fig. 1. This arrangement gives to the gang of chutes 12 a substantially fan-shaped or truncated V-shaped appearance (Fig. 1).

25 Formed in the front wall of each coin chute 12 is a coin-receiving aperture 15 and formed in the outer side wall 33 of each chute 12 (Fig. 5) is a laterally extending slot or opening 16 (Fig. 5). Associated with each slot 16 are the poles 30 17 of a magnet 18; each of these magnets 18 being attached by a bracket 20 to the rear wall of the corresponding coin chute 12.

35 Each of the coin chutes 12 is open at its lower ends to provide a discharge opening and extending horizontally below the open lower ends of the gang or row of coin chutes 12 is a rotatable operating shaft 21 which has a handle 22 (Fig. 1) arranged exteriorly of the vending machine 11 for manipulation by the operator or purchaser. 40 Formed in the operating shaft 21 at spaced intervals axially therealong and in communication with the open lower ends or discharge openings of the coin chutes 12 are coin-receiving pockets 23, each of which is adapted to receive a coin 45 24 of a preselected diameter, thickness, and denomination.

Extending parallel to the operating shaft 22 and supported above the latter on the front wall of the coin chute device is a supporting shaft or 50 rod 25. Swingly mounted on the shaft 25 at spaced intervals axially therealong are stop members 26 each of which has a nose portion 27 that projects into the corresponding coin chute 12 in the front wall of the chute (Figs. 3 and 4). 55

Associated with each of the swinging stops 26 is a resilient coin guiding member 29 which is curved convexly on its outer side (Fig. 3) away from the front of the corresponding coin chute. 5 Each of these coin guiding members 29 is swingingly mounted on the supporting shaft 25 by means of a yoke which includes a pair of spaced arms 30.

Each of the swinging stops 26 is arranged between the arms of the corresponding yoke 30 and 10 each swinging stop 26 is guided in a slot 31 that is formed between a pair of ears or extensions 32 formed on the upper end of each of the coin guiding members 29 (Fig. 1).

15 Operation

When a coin of the proper diameter, thickness, and denomination, is inserted into the coin-receiving aperture 15 of a preselected one of the coin chutes 12, it drops by gravity down the chute 12, traveling along, and bearing by gravity upon the outer inclined side wall 33 of the chute, but being made of non-magnetic material it is not attracted by the poles 17 of the corresponding magnet 18 and passes by the slot 16 down the chute 12 into engagement with the nose portion 27 of the corresponding swinging stop member 26. This engagement of the coin with the swinging stop member 26 slows up the speed of the coin and swings or pivots the stop member 27 (clockwise, Fig. 3) 20 upon its supporting shaft 25, thus opening the lower end of the chute 12 and causing the coin therein to drop slowly down into the corresponding pocket 23 in the operating shaft 21. The operating shaft 21 may then be rotated (counter-clockwise, Fig. 3) by manipulating the handle 22, to complete the vending operation. During this movement of the shaft 21 the coin 24 in its pocket 23 bears at its outer edge against the resilient coin guiding member 29, causing the latter to pivot 25 upon the shaft 25 clockwise (Fig. 3) into the position of Fig. 3. This keeps the coin in its pocket 23 and prevents its discharge therefrom until the shaft 21 has completed half a revolution in making its operating or vending stroke (Fig. 3). During 30 this operation the pivotal movement of the coin guiding member 29 is limited by engagement of the ears 32 of the coin guiding member 29 with the front wall of the coin chute (Fig. 3).

However, if a magnetically attractive disc or substitute 34 for a coin of proper denomination is 35 inserted into one of the coin chutes 12, the same drops down the chute, traveling along the inclined wall 33 thereof, until it comes opposite the corresponding slot 16 (Fig. 5) whereupon it is attracted by the poles 17 of the adjacent magnet 18 and is withdrawn partially out of the chute 12 into the slot 16 where it is held by the magnet, in the position of Fig. 5, until a coin of proper denomination is inserted into the coin chute 12. 40 When this occurs, the coin, traveling down the chute 12 along and bearing against the outside wall 33 thereof, abuts the magnetic disc 35 that is held by the poles 17 of the magnet 18 and pushes or ejects the magnetic disc 35 laterally out of the coin chute 12 through the corresponding slot 16 (to the left, Fig. 5). In this manner magnetic discs or substitutes for the intended coins of proper denominations are prevented from entering the pockets 32 in the shaft 21 and hence are prevented from being discharged by movement of the shaft 21 into the coin receptacle arranged below the shaft 21 (not shown). In this manner fraudulent operation of the vending machine by means of a magnetic disc is prevented.

75 It is to be noted (Fig. 4) that the plates 14 and

19 which form the front and rear walls, respectively, of the coin chutes 12 are so constructed that the coin chutes 12 are angled rearwardly relative to the axis of the shaft 21 and relative to a plane passed vertically through the gang of chutes so that the slug ejecting slots 16 open at the rear side of the rear wall 19 of the gang chute device, as best shown in Fig. 4. This arrangement could be modified, however, by changing the angular position of the individual coin chutes 10 12 so that the slug ejecting slots 16 would open out at the front side of the front wall 14 of the gang chute device instead of at the rear side of the rear wall 19 as shown. This would merely necessitate a rearrangement and reversal of the parts and is considered a variant or modification that is within the scope of the present invention. 15

It is to be noted (Fig. 1) that the horizontal or overall width of the gang chute device 10 at the bottom of the same is considerably less than the horizontal or overall width of the device across the top thereof by reason of the fan-shaped or truncated V-shaped arrangement of the chutes 12 and their convergence at their lower ends toward a common apex or point. This arrangement accommodates the device to the mouth of the coin distributor (not shown) with which the coin chutes are associated and which is considerably narrower in its horizontal width than the top of the cabinet 11 and the overall width of the gang coin chute device 10 at the top of the latter because of the fact that in vending machine cabinets space is at a premium in the cabinet at the point where the upper end or mouth of the coin distributor meets the lower end or bottom of the gang of coin chutes, whereas in the construction of vending machine cabinets ample space is usually found to accommodate the gang of coin chutes at the point where it has its greatest overall width, namely, at the top (Fig. 1). 20 25 30 35 40

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A coin chute device, comprising a gang of coin chutes arranged in a row and all converging toward a common point; each of said chutes having a front wall provided at its upper end with a coin-receiving opening and having a discharge opening at its lower end; each of said chutes having a side wall extending between its coin-receiving opening and its discharge opening that is inclined from the vertical so that a metal disc inserted through the coin-receiving opening of a chute will bear against the said side wall of the chute in traveling by gravity down the chute toward the discharge opening; each of said side walls having a laterally extending slot formed therein; and a magnet associated with each of said slots so as to withdraw thereinto from the corresponding chute a magnetic substitute for the intended coin; each of said chutes being angled rearwardly relative to a plane passed vertically therethrough so that said slots open at their outer ends upon, and discharge magnetic tokens or slugs from, the rear sides of said chutes. 55 60 65 70 75

2. A coin chute device, comprising a gang of

gravity coin chutes divided into groups disposed on opposite sides of the vertical center or middle of the device; each of said chutes having a front wall provided with a coin-receiving aperture and all of said chutes being inclined from the vertical and converging at their lower ends toward a common point so that the overall width of said gang of chutes is less at the lower ends of the chutes than it is at the top of the same; each of said chutes having a side wall extending between its upper and lower ends provided with a laterally extending slot; and a magnet associated with each of said slots so as to withdraw thereinto and at least partially out of the corresponding chute a magnetic disc or substitute for the intended coin; each of said chutes being angled rearwardly relative to a plane passed vertically through said gang of chutes so that the said slots open at their outer ends upon, and discharge magnetic tokens or slugs from, the rear sides of said chutes. 5 10
